(57) **CLAIM**

The ornamental design for a drinking bottle, as shown and described.

DESCRIPTION

FIG. 1 is a front perspective view of a drinking bottle showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a first side elevational view thereof; and,

FIG. 8 is a second side elevational view thereof rotated by 180° relative to the first side elevational view of FIG. 7.

The broken lines in the drawings are included for the purpose of illustration and form no part of the claimed design.
